DESIGN FOR A BILLFOLD

Arnold O. Schoenbeck, West Bend, Wis., assignor to Enger-Kress Company, West Bend, Wis., a corporation of Wisconsin

Application November 22, 1944, Serial No. 116,493

Term of patent 7 years

(Cl. D87—3)

To all whom it may concern:

Be it known that I, Arnold O. Schoenbeck, a citizen of the United States, residing at West Bend, in the county of Washington and State of Wisconsin, have invented a new, original, and ornamental Design for a Billfold, of which the following is a specification, reference being had to the accompanying drawing, forming part thereof.

In the drawing:

I claim:

The ornamental design for a billfold as shown.
ARNOLD O. SCHOENBECK.
